UNITED STATES PATENT OFFICE.

ROBERT E. MOFFITT, OF LUDLOW KENTUCKY.

VALVE.

992,375.

Specification of Letters Patent. Patented May 16, 1911.

Application filed March 7, 1910. Serial No. 547,703.

To all whom it may concern:

Be it known that I, ROBERT E. MOFFITT, a citizen of the United States, and a resident of Ludlow, Kenton county, State of Kentucky, have invented certain new and useful Improvements in Valves; and I do declare the following to be a clear, full, and exact description thereof, attention being called to the accompanying drawing, with the reference characters marked thereon, which form also a part of this specification.

This invention relates to an improved construction of steam-valves and consists of certain novel features, as hereinafter described and pointed out in the claims and as illustrated in the accompanying drawing, in which:—

Figure 1, shows a longitudinal section through the housing of the valve. Fig. 2, shows parts of the preceding figure, partly in section and partly in elevation. Fig. 3, shows in underside view part of the valve-stem. Fig. 4, shows the end of this stem and part of a manipulating handle connected thereto. Fig. 5, is a vertical cross-section of this stem as it appears in Fig. 2, showing also the valve and its position with relation to this stem. Fig. 6, is a vertical cross-section on line 6—6 of Fig. 2.

In the drawing a pipe-conduit is shown of which 9 and 10 are alined parts. Passage through this conduit is controlled by a valve A, of which B is the housing or shell and the wall of which forms an approximately globular inclosure for a chamber b which contains part of the valve-actuating means. This chamber has two oppositely located openings which aline with each other and also with the parts of the pipe-conduit when the housing is connected in position. The wall of this housing is extended around these openings in it, said extensions being so formed as to produce two attaching nipples 11 and 12 which permit the aforementioned connection. The opening at one of these nipples, at 11 in this case, forms the inlet to valve-chamber b and the other forms the outlet from it.

The end of nipple 11 constitutes the seat 50 for valve A, the underside of which is fitted to this seat. Passage through the valve-housing is closed when the valve rests upon this seat as shown in Fig. 1. In Fig.

2, it is shown as raised above this seat and passage is open.

In order to prevent displacement of the valve during its movements, depending wings a are provided on its underside which are fitted to slide within nipple 11. The valve is actuated for raising it by a wedge-shaped cam-block 14, which is connected to a valve-stem 15 supported to permit it to be moved in a longitudinal direction and transverse with reference to the valve-chamber and the alined nipples of the housing. It 65 is supported for such movement at its inner end in a pocket 16 and at its outer portion in a neck 17, both alined transversely to the nipples and formed between them in opposite sides of the housing, these sides being 70 outwardly extended for the purpose.

In assembling, the stem without the cam-block is inserted through the outwardly open neck 17, a stuffing-box 18 being formed in this latter to receive packing, which is held in place by the usual gland 19 and permits formation of a steam tight-joint. The inner part of the inserted stem is seated in the outer part of pocket 16 to which it is fitted. No fit is attempted in the inner part of the 80 pocket where the same is cored out larger to permit necessary clearance of the machine-tool whereby the pocket is formed. Such an enlargement is desirable to prevent resistance to the movement of the valve-stem, by 85 any matter apt to work into this pocket. Such matter, or water for instance, is afforded an escape through a channel, whereby the pocket communicates with the valve-chamber. This channel may be formed by 90 providing a flat place on the inner part of the valve-stem as shown at 21. The cam-block is introduced through one of the nipples and to facilitate its connection to the stem, a cut-out 22 is provided in the side of 95 this latter in which it is seated. A screw 23 completes the connection.

Action on the valve is by means of the cam-surface on the free side of the cam-block which acts on the underside of the 100 valve or on parts connected therewith. In this case it acts on the underside of the wings, which underside is shaped complementary to the cam-surface of the cam-block. The arrangement is by preference so 105 that of four wings provided, the lower

aligned ends of two wings *a* form this underside. A cut-out 24 is provided in the aligned ends of the other two wings whereby the valve, by straddling the block, retains always its proper engagement therewith without interfering with the movement.

Outward movement of the valve-stem by means of a handle 25 raises the valve as shown in Fig. 2. Inward movement permits it to seat as shown in Fig. 1, it seating of course with the pressure.

Proper engagement between block and valve may be adjusted and maintained against wear by the use of washers 26, inserted below the block.

The valve may of course be connected in any position, horizontal, inverted, etc., and therefore means are necessary to prevent it from dropping out of nipple 11, in case it is inverted and the pressure is off. A set-screw 27 is shown in Fig. 2, which is seated in nipple 11 and extends into a notch 28, cut into the edge of one of the wings. A coil-spring 29 is shown in Fig. 1, a boss 31 being provided on the valve whereby, at one of its ends, the spring is held in place. At its other end the spring is held by a bridge 32 which might be provided in an extended part of nipple 11. By preference this extension is provided by means of a separate member or bonnet 33 seated upon nipple 11.

Handle 25 is so connected to the housing that it may be set to move in any plane to suit conditions, or convenience of the operator. For such purpose a coupling ring 34 is used to which the pivotal connection of the handle by means of a link 35 is accomplished. This ring is adjustably seated upon neck 17 so that it may be shifted around on the same until the handle is in the desired position, after which said ring is tightened by means of a screw 36. The handle is loosely jointed to the valve-stem, so that this adjustment of it does not interfere with or affect the position of the stem. This latter is held to the handle, to move it longitudinally, between two shoulders 37 and 38, the inner one of which is formed by reducing the outer end of the stem. The outer one is formed by a nut 38, seated upon this reduced end.

Connection between pipe and valve-housing may be direct to the nipples of this latter, they being threaded for the purpose, or by means of couplings as shown in Fig. 1, 39 and 41 being the complementary members of these couplings, one of which members is connected to the pipe. This manner of connection permits disconnection and removal of the valve without disturbing the pipe-line. The direct connection may be to the outside of the nipples or to their inside, the nipples being preferably threaded, both outside and inside. Such interior connec-

tion as to the upper nipple would have to be made by means of the bonnet.

Disconnection of the parts attached to nipple 11 gives at once access to the valve and to its seat, to permit renewal required, or refitting, without involving any other part of the valve or housing.

Having described my invention, I claim as new:

1. In valve-construction, the combination of a housing having aligned pipe-attaching nipples on opposite sides the outer end of one of which constitutes a valve-seat, a valve fitted to this seat, a valve-stem slidably supported in the housing opposite the inner end of this valve, a cam rigidly connected to this stem and adapted to engage this inner end of the valve for the purpose of actuating it and means to manipulate the valve-stem. 75

2. In valve-construction, the combination of a housing having aligned pipe-attaching nipples on opposite sides the outer end of one of which constitutes a valve-seat, a valve fitted to this seat, a bonnet fitted to this nipple, extending beyond the valve seated on this nipple and adapted for pipe-connection, said bonnet being detachably connected to permit access to the valve-seat, a valve-stem slidably supported opposite the inner side of this valve, means provided on the stem 95 adapted to actuate the valve and means to manipulate the valve-stem. 85

3. In valve-construction, the combination of a housing having pipe-attaching nipples one of which contains a valve-seat, a valve fitted to this seat, a bonnet fitted to this nipple, a spring carried in this bonnet to hold the valve normally seated, a valve-stem slidably supported in the housing, a cam carried on this stem adapted to raise the valve against the action of the spring and means to manipulate this stem. 100

4. In valve-construction, the combination of a housing having pipe-attaching nipples one of which at its outer end contains a valve-seat, a valve for this seat movably fitted to the outer end of this particular nipple and provided with an inclined surface on its inner end, an inclined cam adapted to interact with this inclined surface to 110 actuate the valve and means to operate this cam. 115

5. In valve-construction, the combination of a housing adapted for pipe-connection and provided with a valve-seat, a valve movably fitted to this seat, a valve-stem slidably supported in the housing and provided with a cut-out between its ends, a cam-block for actuating the valve seated in this cut-out portion of the stem and connected to the latter so as to move with it and means to manipulate this stem. 120

6. In valve-construction, the combination

of a housing adapted for pipe-connection and provided with a valve-seat and an outwardly extending neck, a valve movably fitted to the seat, a valve-stem slidably supported in the neck mentioned and outside of which it extends, said stem to be used in connection with the manipulation of the valve, a handle connected between its ends to the free end of this stem and in a manner to 5 permit of it having a rotary adjustment about this free end, a link connected to one of the ends of the handle and a clamping ring adjustably seated on the neck of the housing to which the other end of this link connects.

10 7. In valve-construction, the combination of a substantially globular valve-housing

provided with opposite alined stem-bearings and intermediate inlet and outlet openings, the inlet opening being provided with an external valve-seat, a valve movably fitted 20 to this seat, a stem slidably supported in the bearings in the housing mentioned and adapted for use in connection with the operation of the valve and means to manipulate this stem.

25 In testimony whereof, I hereunto affix my signature in the presence of two witnesses.

ROBERT E. MOFFITT.
